UNITED STATES PATENT OFFICE

CHESTER M. GEORGE AND MARY C. GEORGE, OF NEWPORT, RHODE ISLAND.

SURGICAL INSTRUMENT.

1,231,250.

Specification of Letters Patent. Patented June 26, 1917.

Application filed December 1, 1916. Serial No. 134,453.

To all whom it may concern:

Be it known that we, CHESTER M. GEORGE and MARY C. GEORGE, citizens of the United States, residing at Newport, Newport county, 5 State of Rhode Island, have invented certain new and useful Improvements in Surgical Instruments, of which the following is a specification.

This invention relates to a surgical instrument of the type having two members pivotally connected and formed with a tool means at one end and finger holds at the other end whereby the instrument may be manipulated. The object of the invention is to improve the 15 construction of the finger holds so that the manipulation of the instrument may be facilitated.

The figure in the drawing illustrates the invention as embodied in hemostatic forceps, 20 although it is obvious that the invention may be applied to any form of instrument of this type, such as other types of forceps, scissors, punches, etc. As shown, the device comprises the two members 10 and 11 pivotally 25 connected in any suitable manner at 12 and formed at one of their ends with the tool means 13. At the opposite ends the members are formed with finger holds 14 and 15 and adjacent these holds one of the members as 30 11 may be formed with a series of ratchet teeth 16, which are adapted to coöperate with a ratchet tooth 17 formed on the member 10 to lock the two members in closed position.

35 The improvement constituting the subject matter of this invention consists in forming the finger holds substantially U-shape so that the fingers may be readily withdrawn from the open ends of the said holds. As clearly 40 illustrated these U-shaped holds consist of two substantially parallelly arranged limbs 18 and 19 connected by a curved portion 20, and it will be observed that the two limbs 19 are slightly curved away from each other and 45 that the two outer limbs 18 have a slight reverse curvature, the ends of these lateral limbs being curved slightly outward and away from each other. Thus it will be observed that because of the curvature of the limbs 50 of the finger holds the fingers may very easily enter and leave the holds through the open ends thereof. Furthermore, by forming the limbs slightly curved as stated, it will be apparent that in cases where it is 55 necessary to use the forceps or other instrument to pull on a member this may be more

easily done than if the limbs were straight. The size of the finger holds and spacing apart of the same, of course, may be constructed to fit the hand of the particular 60 surgeon, or operator.

In the use of surgical instruments of the type herein mentioned it is very often necessary to grasp a member or part such as a tissue and then immediately release the instrument. It is obvious and well known that in instruments having the closed ring type finger holds the fingers very often catch in the said holds and that it is always more or less difficult to release the instrument from 70 the fingers. The great advantages of the form of finger holds herein disclosed are obvious.

A surgeon in grasping an instrument does not desire to take time, and usually never 75 does, to grip the instrument in such a manner as to permit a quick release of the same, but he always does grasp it in such a way that he has a positive hold on the same. To do this his fingers and thumb must necessarily pass 80 well into the rings of the finger holds, thereby making it difficult to release the instrument. It is especially discomforting and exasperating to have an instrument remain in the hand when immediate release without 85 especial effort or attention is desired. The open finger holds as described facilitate the releasing of the instrument thereby increasing the precision, exactness and speed with which the instrument can be used without 90 impairing the essential purpose of the same.

Having thus described the invention, what is claimed and desired to be secured by Letters Patent is:

1. In a surgical instrument comprising 95 two members pivoted together intermediate their ends and each having tool means at one end and a finger hold at the other end, and means for locking the two members in closed position, the improvement which consists in forming said holds substantially U-shaped and arranged with the opening at the rear end of the hold whereby the fingers may be easily withdrawn rearwardly from the holds. 100

2. In a surgical instrument comprising 105 two members pivoted together intermediate their ends and each having tool means at one end and a finger hold at the other end and means for locking the two members in closed position, the improvement which consists in forming said holds substantially U-

shaped with the two inner limbs curved slightly away from each other and the ends of the outer limbs also being curved away from each other, said holds arranged with 5 the openings therein at the rear end of the hold.

3. In a surgical forceps comprising two members pivoted together intermediate their ends and each having gripping means at 10 one end and a finger hold at the other end and means for locking the two members in

gripping position, the improvement which consists in forming said holds substantially U-shaped with the outer limbs reversely curved, the outer ends thereof being curved 15 slightly outward and away from each other and said holds arranged with the openings therein at the rear of the hold.

In testimony whereof we affix our signatures.

CHESTER M. GEORGE.
MARY C. GEORGE.
